Patented June 20, 1961

190,637

FENDER ORNAMENT FOR AUTOMOBILES OR THE LIKE

George W. Walker, Bloomfield Hills, Mich., assignor to Ford Motor Company, Dearborn, Mich., a corporation of Delaware

Filed Dec. 5, 1960, Ser. No. 63,110

Term of patent 7 years

(Cl. D14—6)

FIGURE 1 is a perspective view of a fender ornament for automobiles or the like, showing my new design;

FIGURES 4, 5, 6, 7, 8 and 9 are sectional views taken on the planes indicated by the lines 4-4, 5-5, 6-6, 7-7, 8-8 and 9-9, respectively, of FIGURE 2.

I claim:

The ornamental design for a fender ornament for automobiles or the like, substantially as shown.
